INSOLE-PUNCHING MACHINE

Bernhardt Jorgensen, Marblehead, Mass., assignor to United Shoe Machinery Corporation, Flemington, N. J., a corporation of New Jersey

Application May 24, 1941, Serial No. 395,036

45 Claims. (Cl. 164—86)

This invention relates primarily to machines for punching holes in insoles, but it will be understood that as to some of its novel features it is not limited in utility to machines for performing operations of that particular character or to machines for operating on that particular kind of work.

An immediate object of the invention is to provide a machine for punching in insoles holes to be used in positioning shoes in shoe machines in accordance with a method claimed in a copending application of mine, Serial No. 395,037, filed on May 24, 1941. To insure that the positions of the shoes in such shoe machines will not be affected by variations in the positions of the insoles on their lasts, it is preferable to punch the holes in the insoles with the insoles mounted on the lasts and held in fixed relation thereto, and the present invention, in one aspect, accordingly provides a machine for this purpose, the machine herein shown having a pair of punches which punch corresponding holes in the forepart of each insole in accurately predetermined locations farther inwardly from the edge of the insole than the margin of the upper extends when in lasted position. For the sake of special accuracy in positioning shoes in machines which operate on the uppers, such as toe-lasting machines, it is also preferable that the locations of the holes in the insole be determined by reference to the outer face of an upper also mounted on the last and, it may be, partially shaped over the last. Accordingly, the machine herein shown is provided with gage mechanism which by engagement with the outer face of the upper, if there is an upper on the last, positions the last and its shoe materials, herein frequently referred to inclusively as the shoe, lengthwise, laterally and angularly for the insole-punching operation, the term "angularly" being used herein with reference to orientation of the shoe about an axis extending heightwise thereof. In the construction shown the punches act on the insole in response to heightwise movement of the shoe effected by a toe rest which engages the shoe at the top of the forepart, the movement of the shoe being limited by stop mechanism comprising a shoe rest member engaged by the insole and mounted for limited movement in response to the pressure of the insole thereon. Preferably, as illustrated, the punches are solid punches having conical insole-engaging ends; and by reason of the shape of the punches, the character of the force applied in the insole-punching operation and the fact that the movement of the shoe is

limited as above explained, the punches penetrate only part way through the insole, so that the holes are not visible on the inner face of the insole.

5 The above-mentioned gage mechanism, in the machine herein shown, comprises a toe-end gage which determines the position of the shoe lengthwise and against which the operator presses the toe-end face of the shoe in presenting the shoe to the machine, and opposite side gages which by engagement with the sides of the shoe determine its position laterally and angularly. To facilitate the presentation of the shoe to the machine and to avoid any danger of injuring the upper by frictional action of the side gages thereon if there is an upper on the last, the invention further provides a construction whereby the side gages are moved toward each other to position and clamp the shoe by power-operated means after the shoe has been presented against the toe-end gage, this power-operated means being started in operation by the pressure of the shoe against the toe-end gage. More particularly, in the construction shown, the side gages are moved into their operative positions by fluid-operated means, and fluid is admitted to this fluid-operated means by a valve which is operated by electrical means energized by the movement of the toe-end gage. In accordance with a further 10 characteristic of the illustrative embodiment of the invention the toe rest which moves the shoe to render the punches effective on the insole is operated by additional fluid-operated means controlled by the means which operates the side gages in the manner above described. The power operation of the whole machine is thus responsive to electrical control through the pressure of the shoe on the toe-end gage. In response to the movement of the shoe by the toe rest in the insole-punching operation the electrical control of the machine is terminated, whereupon the parts are returned by springs or 15 by gravity to their starting positions.

20 The above and other features of the invention, including novel means for controlling the punches in such manner as to equalize the forces which they apply to the work while permitting them to adjust themselves to the contour of the work, novel side gage mechanism, and various 25 novel details of construction and combinations of parts, will now be more particularly described with reference to the accompanying drawings and thereafter pointed out in the claims.

25 In the drawings,

30 Fig. 1 is a view in left-hand side elevation of

the upper portion of a machine in which the invention is embodied, with parts broken away, illustrating by dot-and-dash lines the position of a shoe before the operation of the machine is started;

Fig. 2 shows the same portion of the machine in front elevation, with parts broken away;

Fig. 3 is a section on the line III—III of Fig. 2, illustrating the position of the shoe as in Fig. 1;

Fig. 4 is a section on the line IV—IV of Fig. 2;

Fig. 5 is a view similar to the upper portion of Fig. 1, with parts broken away, showing the shoe in position to start the machine;

Fig. 6 is a view similar to Fig. 5, but with other portions of the structure broken away, showing the parts as they are positioned at the end of the insole-punching operation;

Fig. 7 is a section on the line VII—VII of Fig. 6, on an enlarged scale, better illustrating the relation of the punches to the insole; and

Fig. 8 is a view similar to Fig. 3, but with parts omitted and with the parts which are visible positioned as they are in Fig. 6.

The machine is provided with a column 2 adapted to rest on the floor, and secured to this column is an upwardly extending frame plate 4. Fast on the plate 4 is a casting 6 to which are secured a pair of upwardly extending rods 8, and secured to the upper ends of these rods is a crossbar 10 which serves as a support for a rearwardly extending block 12. Slidably mounted for vertical movements in the crossbar 10 are two punches 14 having pointed lower ends of conical shape arranged to punch holes part way through the insole a of a shoe on its last when the shoe is forced upwardly against the punches by means hereinafter described. Each of the punches 14 is provided with an enlarged cylindrical head 16 slidably movable in a bore in the crossbar 10 and controlled by a light spring 18 which tends to force the punch upwardly. The two heads 16 are engaged above by the opposite end portions of an equalizing lever 20 which is fulcrumed midway between its opposite ends on a sleeve 22 surrounding a screw 24, this being one of two screws for securing the block 12 to the crossbar 10. The heads 16 are located at equal distances from the fulcrum of the lever. It will be understood that through the lever 20 the forces applied by the two punches 14 to the insole are substantially equalized while the punches are permitted to adjust themselves to the contour of the bottom of the last, so that they are forced substantially equal distances into the insole.

Mounted for vertical movement in the block 12 is the stem 26 of a shoe rest member 28 arranged to engage the bottom face of the extreme toe end of the insole when the shoe is initially presented to the machine, as illustrated diagrammatically in Fig. 1. In engagement with the upper end of the stem 26 is a spring 30 which tends to force the member 28 downwardly and holds it initially in a position determined by the engagement of a screw 32 in the stem with the block 12 at the lower end of a slot 34 in the block. The member 28 thus serves as means for initially positioning the shoe heightwise with the insole slightly below the punches 14. The position of the shoe lengthwise in the operation of the machine is determined by an end gage 36 against which the operator presses the toe-end face of the shoe and which in response to the pressure of the shoe thereon swings rearwardly about a pivotal support 38 on the block 12 to a position adjustably determined by its contact with a screw

40 threaded in the frame plate 4. A spring 41 holds the end gage initially in contact with the rear face of the block 12. The position of the shoe laterally and angularly relatively to the punches 14 is determined by two pairs of side gages 42 and 44 (Fig. 3) which are in the nature of bell-crank levers and are mounted on vertical shafts 46 rotatable in brackets 48 and 50 fast on the frame plate 4. The two gages 42 are arranged to act on the shoe at the opposite sides of the forepart in the vicinity of its ball portion and are connected together by gear segments 52 (Fig. 3) so that their movements toward or from each other widthwise of the shoe are equalized. The two gages 42 are supported on the bracket 48, the left-hand gage being secured by a set screw 54 to the shaft 46 on which it is mounted and the right-hand gage being loosely mounted on the other shaft 46. The two gages 44 are arranged to act on the shoe at the opposite sides of its toe portion and are connected together for equal movements toward or from each other by gear segments 56. The gages 44 are supported on the gages 42, the right-hand gage being secured by a set screw 58 to its shaft 46 and the left-hand gage being loose on the other shaft. It will thus be seen that one pair of gages are movable by one of the shafts 46 and the other pair by the other shaft. A spring 60 connected to pins on the two shafts tends to turn the shafts in directions to retract the gages from the sides of the shoe and maintains them initially in positions determined by a stop pin 62 which extends upwardly from the bracket 48. In order to guard against any marking of the shoe upper by pressure of the side gages thereon, a flexible strap 64 which may be made of leather is connected to the two gages 42 and 44 at each side of the shoe in position to contact with the upper when the gages are swung inwardly toward the shoe. One end of each strap is fast on a plate 66 pivotally mounted on a pin 68 on the gage 42, and the other end of the strap is fast on a pin 70 extending downwardly from the gage 44 in fixed relation thereto.

Fast on each shaft 46 above the bracket 50 is an arm 72, and loosely mounted on each shaft below the bracket is an arm 74 supported by a washer 75 on the lower end of the shaft. Associated with each pair of arms 72 and 74 is a compression spring 76 one end of which abuts against a block 78 (Fig. 1) swiveled to turn about a vertical axis on the arm 72 and the other end of which abuts against a block 80 swiveled to turn about a vertical axis on the arm 74. Extending through both these blocks and the spring is a rod 82 (Fig. 4) provided with a head 84 for engaging the block 78 and with a nut 86 for engaging the block 80. It will thus be seen that swinging movement may be imparted yieldingly to the arm 72 through the spring 76 by movement of the arm 74. Swinging movements of both arms 74 to move the gages 42 and 44 toward the shoe into their operative positions are effected by a bell-crank lever 88 (Fig. 1) which is pivotally mounted on a bracket 90 fast on the frame plate 4 and has an upwardly extending curved arm 92 arranged to engage the arms 74 as illustrated in Fig. 4. A rearwardly extending arm 94 of the bell-crank lever 88 has depending therefrom a rod 96 the lower end of which is connected to a lever 98 pivotally mounted at its front end on a bracket 100 fast on the column 2. The rear end of the lever 98 is pivotally connected to a link 102 which is connected at its upper end to a piston 104 movably mounted in a

cylinder 106. This cylinder is supported at its upper end by a pin 108 on a bracket 110 fast on a plate 112 which is secured to the bracket 100. It will thus be seen that in response to downward movement of the piston 104 the bell-crank lever 88 is operated to swing the two arms 74 (Fig. 4) in opposite directions, respectively, and thus to impart to the side gages 42, 44 their shoe-positioning and clamping movements, each of the springs 76 yielding as required when the pair of gages 42 or 44 controlled thereby are stopped by the resistance of the shoe to their further movements. Downward movement of the piston 104 is limited by engagement of the lower end of the link 102 with a screw 114 threaded in a lug on the plate 112.

The piston 104 is preferably operated by compressed air which may be obtained from a source of factory supply if such is available or may be supplied by a suitable pump. As illustrated, a pipe 116 leads from the source of supply and communicates with a pipe 118 which extends rearwardly and then toward the left to valve mechanism 120 from which a pipe 122 leads to the upper end of the cylinder 106. The valve mechanism 120 (Fig. 2) comprises a tube 124 which is clamped between a boss 126 on the plate 112 and a bar 128 secured to this plate. The tube 124 is divided between its opposite ends by a partition 130, and its opposite ends are in communication, respectively, with the pipe 118 and the pipe 122. Extending through the tube at the opposite sides respectively, of the partition 130 are two sets of ports 132 and 134. Slidably mounted on the tube is a sleeve valve 136 provided with an annular chamber 138. When the valve is in the position illustrated in Fig. 2 the ports 132 leading from the pipe 118 are closed and the ports 134 leading from the pipe 122 are open to exhaust. Movement of the valve toward the left from that position serves to establish communication between the ports 132 and 134, so that compressed air is admitted to the cylinder 106 to operate the piston 104. The valve is controlled by a lever 140 which is pivotally mounted between its opposite ends on a member 142 secured to the plate 112 and is provided at its upper end with a pin 144 extending into an annular groove 146 in the valve. A spring 148 connected to the pin 144 holds the valve initially in its idle position against the boss 126, as illustrated in Fig. 2.

To move the valve 136 into position to admit compressed air to the cylinder 106 the lever 140 is operated by electrical means comprising a solenoid 150 arranged to act on a plunger 152 connected by a link 154 to the lower end of the lever. Current is supplied to the solenoid from any suitable source through wires 156 which lead to a switch 158 (Fig. 1) mounted in a casing 160 fast on a bracket 162 secured to the bracket 48. The switch 158 is closed to cause current to flow through the solenoid 150 by rearward movement of a plunger 164 against the resistance of a spring 166. Such movement of the plunger is effected by rearward swinging movement of the toe-end gage 36 in response to the pressure of the shoe thereon when the operator presents the shoe to the machine. For this purpose there is pivotally mounted on the gage a pawl 168 the rear end of which is normally positioned opposite the front end of the plunger 164, as shown in Fig. 1, and the front end of which extends into a recess 170 formed in the stem 26. A spring-pressed pin 172 in the gage 36 tends to lift the rear end

of the pawl 168 and holds it normally in the position in which it is shown in Fig. 1.

In the machine herein shown the operation of the punches 14 to punch the holes in the insole 5 results from upward movement of the shoe relatively to the punches. For thus moving the shoe there is provided a toe rest 174 mounted on the upper end of a plunger or piston 176 which is vertically movable in a bore in the casting 6, this casting being so formed as to provide a cylinder 178 for the piston. Compressed air is admitted to the lower end of the cylinder 178 from the supply pipe 116 through a pipe 180 and valve mechanism 182 which is similar to the previously 10 described valve mechanism 120. Briefly, this valve mechanism comprises a tube 184 clamped between a bar 186 and a nipple 188 at the lower end of the cylinder 178, the upper end of the tube communicating with the cylinder and the lower end with the pipe 180. The tube is divided 15 by a partition 190 extending between two sets of ports 192 and 194. Movable on the tube is a sleeve valve 196 which in its normal position in engagement with the bar 186 closes the ports 194 and opens the ports 192 to exhaust. The valve is moved upwardly to establish communication between the two sets of ports and thus to admit compressed air to the cylinder 178 by a lever 198 provided with a pin 200 which extends 20 into an annular groove 202 in the valve, the lever being pivotally mounted between its ends on a pin 204 supported on a block 206 fast on the frame plate 4. The rear end of the lever 198 is pivotally connected to a block 208 which is 25 slidably mounted on the rod 96 and rests normally against a collar 210 fast on the rod. Between this block and another collar 212 also fast on the rod is a compression spring 214. It will thus be seen that the movement of the lever 198 to operate the valve 196 in the manner above described 30 is derived from the downward movement of the rod 96 effected by the piston 104. The lever 198, however, is initially held against such valve-operating movement by a latch 216 pivotally 35 mounted on the block 206 and held by a spring 218 in a notch 220 in the lever. Accordingly, the spring 214 is compressed by the downward movement of the rod 96 until the side gages 42 and 44 have been moved into positions to clamp the shoe. Thereafter, as the rod continues its downward movement, the latch 216 is withdrawn from the notch 220 by a collar 222 which is fast on the rod 96 and has a conical face 224 arranged 40 to engage a pin 226 carried by the latch. The spring 214 then expands and operates the lever 198 to move the valve 196 into position to admit compressed air to the cylinder 178, whereupon 45 the toe rest 174 is lifted and forces the shoe up against the punches 14. Such upward movement 50 of the shoe is limited by contact of the screw 32 in the stem 26 with the block 12 at the upper end of the slot 34, as illustrated in Fig. 6. It will be understood that the pressure of the gages 55 on the shoe is such as readily to permit the upward movement of the shoe to take place. Patentable novelty involved in the above-described 60 means for operating the valve 196 is claimed in a copending application of mine for Letters Patent for improvements in Machine for use in the manufacture of shoes, Serial No. 377,347, filed 65 on February 4, 1941.

As further illustrated in Fig. 6, the upward movement of the stem 26 which results from the above-described upward movement of the shoe lifts the front end of the pawl 168 and

thereby causes its rear end to release the plunger 164, so that the spring 166 opens the switch 158. This results in breaking the circuit through the solenoid 150, thereby permitting the spring 148 to return the valve 136 to its initial position and thus to open the cylinder 106 to exhaust. The springs 60 and 76 then operate to return the side gages 42 and 44 to their initial positions and also to impart return movement to the bell-crank lever 88. In response to such movement of the bell-crank lever the lever 198 is returned to its initial position where it is held by the latch 216, thereby returning the valve 196 and opening the cylinder 178 to exhaust, so that the toe rest 174 is moved downwardly away from the shoe by gravity.

The manner of operation of the machine will now be briefly summarized. Since the machine is designed to operate on insoles mounted on lasts, such an insole will have been mounted on its last and preferably fastened thereto, as by temporary tacks, in the customary manner; and an upper also may have been assembled on the last and partially shaped thereover, especially if it is desired to determine the locations of the holes in the insole by reference to the outer face of the upper. As herein illustrated by way of example, such an upper has been subjected to the usual pulling-over operation and has also been lasted along its sides rearwardly of its toe portion before the shoe is presented to the machine. In presenting the shoe the operator engages the bottom face of the toe end of the insole with the shoe rest member 28 and the toe-end face of the upper with the end gage 36, as illustrated in Fig. 1, the toe end of the shoe being spaced somewhat above the toe rest 174. At this time the side gages 42 and 44 are sufficiently retracted to facilitate movement of the shoe into position between them and to prevent any substantial rubbing of the straps 64 on the sides of the upper. By pressure of the shoe against the end gage 36 this gage is then moved rearwardly to the position idetermined by the stop screw 40, as shown in Fig. 5, and as a result of this movement of the gage the switch 158 is operated to energize the solenoid 150. By the action of the solenoid the valve 136 is moved into position to admit compressed air to the cylinder 106, whereupon the piston 104 is moved downwardly to the position determined by the stop screw 114. By the downward movement of this piston the bell-crank lever 88 is operated to swing the side gages 42 and 44 inwardly toward each other and to cause them to position the shoe laterally and angularly in proper relation to the punches 14. By the same movement of the piston 104 the spring 214 is compressed and then the latch 216 is operated to release the lever 198 to the action of the spring, whereupon the lever is operated by the spring to move the valve 196 into position to admit compressed air to the cylinder 178. By the action of the piston 176 the toe rest 174 is then moved upwardly against the toe end of the shoe and imparts upward movement to the shoe to cause the punches 14 to punch the holes in the insole, as shown in Fig. 6, the upward movement of the shoe being limited by the shoe rest member 28 which moves upwardly only as far as permitted by the screw 32 and the slot 34. In this insole-punching operation the two punches 14 are controlled by the equalizing lever 20 which permits them to adjust themselves to the contour of the bottom of the last and causes them thereafter to act with substantially equal forces to 75

punch the holes part way through the insole. The holes thus formed are shown at *b* in Fig. 8. In response to the upward movement of the shoe rest member 28 the pawl 168 is swung into position to release the plunger 164, as shown in Fig. 6, whereupon the spring 166 moves this plunger reversely to open the switch 158 and thus to de-energize the solenoid 150. The spring 148 then returns the valve 136 to its initial position, releasing the compressed air from the cylinder 106. By the action of the springs 60 and 76 the side gages are then returned to their initial positions and the bell-crank lever 88 is operated to return the piston 104 and also to return the lever 198 into the position where it is held by the latch 216. Such return movement of the lever 198 returns the valve 196, thus releasing the compressed air from the cylinder 178 and permitting the toe rest 174 to be moved downwardly by gravity. The operator then removes the shoe, whereupon the shoe rest member 28 and the end gage 36 are returned by the springs which control them, the pawl 168 resuming its initial relation to the plunger 164.

Having described the invention, what I claim as new and desire to secure by Letters Patent of the United States is:

1. In an insole-punching machine, insole-punching mechanism arranged to operate on insoles mounted on lasts to punch in each insole at one operation a plurality of holes located farther inwardly from the edge of the insole than the margin of the shoe upper extends when in lasted position, and means for effecting relative movement of each last and said punching mechanism in a direction heightwise of the last to cause said mechanism thus to operate on the insole.

2. In an insole-punching machine, insole-punching mechanism arranged to operate on insoles mounted on lasts to punch holes in the insoles, means for moving each last heightwise relatively to said punching mechanism to cause said mechanism to operate on the insole, and stop mechanism for limiting such movement of the last.

3. In an insole-punching machine, insole-punching mechanism arranged to operate on insoles mounted on lasts to punch holes in the insoles, means for moving each last heightwise relatively to said punching mechanism to cause said mechanism to operate on the insole, a member arranged to engage the insole and movable by the last in response to pressure of the insole thereon, and means for limiting the movement of said member and for thereby limiting the heightwise movement of the last.

4. In an insole-punching machine, insole-punching mechanism arranged to operate on insoles mounted on lasts to punch holes in the insoles, fluid-operated means for effecting relative movement of each last and said punching mechanism to cause said mechanism to operate on the insole, and stop mechanism for limiting said relative movement.

5. In an insole-punching machine, insole-punching mechanism arranged to operate on insoles mounted on lasts to punch in each insole a plurality of holes located farther inwardly from the edge of the insole than the margin of the shoe upper extends when in lasted position, said mechanism comprising solid punches having pointed insole-engaging ends, and means for effecting relative movement of each last and said punches to cause them to penetrate only part way through the insole.

6. In an insole-punching machine, insole-punching mechanism arranged to operate on the foreparts of insoles mounted on lasts to punch holes in the insoles, and a member for moving each last heightwise relatively to said punching mechanism by pressure on the top of the forepart of the last to cause said mechanism to operate on the insole.

7. In an insole-punching machine, insole-punching mechanism arranged to operate on the foreparts of insoles mounted on lasts to punch holes in the insoles, a fluid-operated device for moving each last heightwise relatively to said punching mechanism by pressure on the top of the forepart of the last to cause said mechanism to operate on the insole, and means for admitting operating fluid to said device to operate it.

8. In an insole-punching machine, insole-punching mechanism arranged to operate on the foreparts of insoles mounted on lasts to punch holes in the insoles, a toe rest for moving each last heightwise relatively to said punching mechanism by pressure on the top of the forepart of the last to cause said mechanism to operate on the insole, and a member arranged to engage the bottom face of the forepart of the insole to position the last heightwise in spaced relation to said toe rest when the work is presented to the machine, said member being movable with the last in the insole-punching operation in response to pressure of the insole thereon.

9. In an insole-punching machine, insole-punching mechanism arranged to operate on insoles mounted on lasts to punch holes in the insoles, a gage for positioning each last and its insole relatively to said punching mechanism when the work is presented to the machine, and power-operated means controlled by said gage for effecting relative movement of the last and said punching mechanism to cause the latter to operate on the insole in response to pressure of the last on the gage.

10. In an insole-punching machine, insole-punching mechanism arranged to operate on insoles mounted on lasts to punch holes in the insoles, a gage for positioning each last and its insole relatively to said punching mechanism when the work is presented to the machine, power-operated means for effecting relative movement of the last and said punching mechanism to cause the latter to operate on the insole, and electrical means controlled by said gage for rendering said power-operated means thus operative.

11. In an insole-punching machine, insole-punching mechanism arranged to operate on insoles mounted on lasts to punch holes in the insoles, a gage for positioning each last and its insole relatively to said punching mechanism when the work is presented to the machine, fluid-operated means for effecting relative movement of the last and said punching mechanism to cause the latter to operate on the insole, and mechanism controlled by said gage for admitting operating fluid to said fluid-operated means in response to pressure of the last on the gage.

12. In an insole-punching machine, insole-punching mechanism arranged to operate on insoles mounted on lasts to punch holes in the insoles, a gage for positioning each last and its insole relatively to said punching mechanism when the work is presented to the machine, fluid-operated means for effecting relative movement of the last and said punching mechanism to cause the latter to operate on the insole, a valve for

admitting operating fluid to said fluid-operated means, power-operated means for operating said valve thus to admit the fluid, and electrical means controlled by said gage for rendering said power-operated means effective thus to operate the valve.

13. In an insole-punching machine, insole-punching mechanism arranged to operate on insoles mounted on lasts to punch holes in the insoles, a gage for positioning each last and its insole relatively to said punching mechanism when the work is presented to the machine, power-operated means for effecting relative movement of the last and said punching mechanism to cause the latter to operate on the insole, electrical means for rendering said power-operated means thus operative, a switch controlled by said gage for energizing said electrical means in response to pressure of the last on the gage, and automatic means for thereafter operating said switch to de-energize said electrical means while the last is still pressing on the gage.

14. In an insole-punching machine, insole-punching mechanism arranged to operate on insoles mounted on lasts to punch holes in the insoles, a gage for positioning each last and its insole relatively to said punching mechanism when the work is presented to the machine, power-operated means for moving the last heightwise relatively to said punching mechanism to cause the latter to operate on the insole, electrical means for rendering said power-operated means thus operative, a switch for energizing said electrical means, a member for thus operating said switch by movement of the gage in response to pressure of the last on the gage, means for operating said member by the heightwise movement of the last to release said switch, and a spring for then operating the switch to terminate electrical control of said power-operated means.

15. In an insole-punching machine, insole-punching mechanism arranged to operate on insoles mounted on lasts to punch holes in the insoles, gaging means movable to position each last and its insole relatively to said punching mechanism, power-operated means for thus operating said gaging means, additional power-operated means for effecting relative movement of the last and said insole-punching mechanism to cause the latter to operate on the insole, and mechanism for starting the operation of said additional power-operated means in response to the movement of said first-named power-operated means.

16. In an insole-punching machine, insole-punching mechanism arranged to operate on insoles mounted on lasts to punch holes in the insoles, gaging means movable to position each last and its insole relatively to said punching mechanism, fluid-operated means for thus operating said gaging means, additional fluid-operated means for effecting relative movement of the last and said insole-punching mechanism to cause the latter to operate on the insole, and mechanism for admitting operating fluid to said additional fluid-operated means in response to the movement of said first-named fluid-operated means.

17. In an insole-punching machine, insole-punching mechanism arranged to operate on insoles mounted on lasts to punch holes in the insoles, gaging means movable to position each last and its insole relatively to said punching mechanism, fluid-operated means for thus oper-

ating said gaging means, additional fluid-operated means for effecting relative movement of the last and said insole-punching mechanism to cause the latter to operate on the insole, a valve for admitting operating fluid to said additional fluid-operated means, a member for operating said valve thus to admit the fluid, a spring for operating said member, means for energizing said spring by movement of said first-named fluid-operated means, and mechanism also controlled by said first-named means for holding said member against movement by the spring and for thereafter releasing it to the action of the spring.

18. In an insole-punching machine, insole-punching mechanism arranged to operate on insoles mounted on lasts to punch holes in the insoles, gaging means movable to position each last and its insole relatively to said punching mechanism, fluid-operated means for thus operating said gaging means, additional fluid-operated means for effecting relative movement of the last and said insole-punching mechanism to cause the latter to operate on the insole, a valve for admitting operating fluid to said additional fluid-operated means, a lever for operating said valve thus to admit the fluid, a spring for operating said lever, a latch for holding the lever initially against movement by the spring, and mechanism movable by said first-named fluid-operated means first to energize said spring and thereafter to operate said latch to release said lever.

19. In an insole-punching machine, insole-punching mechanism arranged to operate on insoles mounted on lasts to punch holes in the insoles, gage mechanism comprising a toe-end gage and opposite side gages for positioning each last and its insole relatively to said punching mechanism, and power-operated means for moving the side gages toward each other into their operative positions and for effecting relative movement of the last and said punching mechanism to cause said mechanism to operate on the insole after the last has been presented in a position determined by said toe-end gage.

20. In an insole-punching machine, insole-punching mechanism arranged to operate on the foreparts of insoles mounted on lasts to punch holes in the insoles, gage mechanism comprising a toe-end gage and opposite side gages for positioning each last and its insole relatively to said punching mechanism, a toe rest for moving each last heightwise relatively to said punching mechanism by pressure on the top of the forepart of the last to cause said mechanism to operate on the insole, and power-operated means for moving the side gages toward each other into their operative positions and for operating said toe rest after the last has been presented in a position determined by said toe-end gage.

21. In an insole-punching machine, insole-punching mechanism arranged to operate on insoles mounted on lasts to punch holes in the insoles, gage mechanism comprising a toe-end gage and opposite side gages for positioning each last and its insole relatively to said punching mechanism, power-operated means for moving the side gages toward each other into their operative positions and for effecting relative movement of the last and said punching mechanism to cause said mechanism to operate on the insole after the last has been presented in a position determined by said toe-end gage, and means for starting the operation of said power-operated means in re-

sponse to pressure of the last on said toe-end gage.

22. In an insole-punching machine, insole-punching mechanism arranged to operate on insoles mounted on lasts to punch holes in the insoles, gage mechanism for positioning each last and its insole relatively to said punching mechanism, said gage mechanism comprising a toe-end gage for positioning the last lengthwise and side gages movable toward each other further to position the last between them, power-operated means for moving the side gages into their operative positions, mechanism for starting the operation of said power-operated means in response to pressure of the last on said toe-end gage, additional power-operated means for effecting relative movement of the last and said insole-punching mechanism to cause the latter to operate on the insole, and mechanism for starting the operation of said additional power-operated means by the movement of said first-named power-operated means.

23. In an insole-punching machine, insole-punching mechanism arranged to operate on insoles mounted on lasts to punch holes in the insoles, gage mechanism for positioning each last and its insole relatively to said punching mechanism, said gage mechanism comprising a toe-end gage for positioning the last lengthwise and side gages movable toward each other further to position the last between them, fluid-operated means for moving the side gages into their operative positions, mechanism for admitting operating fluid to said fluid-operated means in response to pressure of the last on said toe-end gage, additional fluid-operated means for effecting relative movement of the last and said insole-punching mechanism to cause the latter to operate on the insole, and mechanism for admitting operating fluid to said additional fluid-operated means in response to the movement of said first-named fluid-operated means.

24. In an insole-punching machine, insole-punching mechanism arranged to operate on insoles mounted on lasts to punch holes in the insoles, gage mechanism for positioning each last and its insole relatively to said punching mechanism, said gage mechanism comprising a toe-end gage for positioning the last lengthwise and side gages movable toward each other further to position the last between them, fluid-operated means for moving the side gages into their operative positions, a valve for admitting operating fluid to said fluid-operated means, electrical means controlled by the toe-end gage for operating said valve, additional fluid-operated means for effecting relative movement of the last and said insole-punching mechanism to cause the latter to operate on the insole, a valve for admitting operating fluid to said additional fluid-operated means, and mechanism for operating said last-named valve by said first-named fluid-operated means.

25. In an insole-punching machine, insole-punching mechanism arranged to operate on insoles mounted on lasts to punch holes in each insole, said mechanism comprising a pair of punches relatively movable in directions heightwise of the last, and an equalizer for controlling said punches to cause them to act on the insole with substantially equal forces in the insole-punching operation while permitting them to adjust themselves to the contour of the bottom of the last.

26. In the insole-punching machine, insole-punching mechanism arranged to operate on in-

soles mounted on lasts to punch holes in each insole, said mechanism comprising a pair of punches relatively movable in directions heightwise of the last, and an equalizing lever arranged to engage said punches respectively at equal distances from its fulcrum to cause the punches to act on the insole with substantially equal forces in the insole-punching operation while permitting them to adjust themselves to the contour of the bottom of the last.

27. In an insole punching machine, a pair of punches arranged to operate on insoles mounted on lasts to punch holes in each insole, said punches being relatively movable in lengthwise directions heightwise of the last, an equalizing lever arranged to control said punches by engaging them at substantially equal distances from its fulcrum while permitting them to adjust themselves to the insole, and springs associated respectively with the different punches and arranged to urge them toward said lever.

28. In a machine for operating on shoes comprising insoles and uppers mounted on lasts, insole-punching mechanism arranged to punch holes in the insoles on the lasts, and gage mechanism for positioning each shoe relatively to said insole-punching mechanism by engagement with the outer face of the upper simultaneously in a plurality of locations exteriorly of the shoe bottom.

29. In a machine for operating on shoes comprising insoles and uppers mounted on lasts, insole-punching mechanism arranged to punch holes in the foreparts of the insoles on the lasts, and gage mechanism for positioning each shoe relatively to said insole-punching mechanism by engagement with the outer face of the upper, said gage mechanism comprising a toe-end gage for positioning the shoe lengthwise and side gages for further positioning it laterally and angularly by pressure on the opposite sides of its forepart.

30. In a machine for operating on shoes comprising insoles and uppers mounted on lasts, insole-punching mechanism arranged to punch holes in the insoles on the lasts, gage mechanism comprising a toe-end gage and opposite side gages for positioning each shoe relatively to said insole-punching mechanism by engagement with the upper, and power-operated means for moving the side gages toward each other to position and clamp the shoe after the shoe has been presented against said toe-end gage.

31. In a machine for operating on shoes comprising insoles and uppers mounted on lasts, insole-punching mechanism arranged to punch holes in the insoles, gage mechanism comprising a toe-end gage and opposite side gages for positioning each shoe relatively to said insole-punching mechanism by engagement with the upper, power-operated means for moving the side gages toward each other to position and clamp the shoe after the shoe has been presented against said toe-end gage, and mechanism for starting the operation of said power-operated means in response to pressure of the shoe on said end gage.

32. In a machine for operating on shoe material mounted on lasts, the combination with means for operating on the material, of gage mechanism for positioning each last and its shoe material relatively to said operating means, said gage mechanism comprising a toe-end gage for positioning the last lengthwise and side gages movable toward each other further to position

the last between them, power-operated means for moving the side gages into their operative positions, and mechanism for starting the operation of said power-operated means in response to pressure of the last on said toe-end gage.

5 33. In a machine for operating on shoe material mounted on lasts, the combination with means for operating on the material, of gage mechanism for positioning each last and its shoe material relatively to said operating means, said gage mechanism comprising a toe-end gage for positioning the last lengthwise and side gages movable toward each other further to position the last between them, power-operated means 15 for moving the side gages into their operative positions, electrical means for starting the operation of said power-operated means, and a switch controlled by said toe-end gage for energizing said electrical means in response to pressure of the last on said end gage.

10 34. In a machine for operating on shoe material mounted on lasts, the combination with means for operating on the material, of gage mechanism for positioning each last and its shoe material relatively to said operating means, said gage mechanism comprising a toe-end gage for positioning the last lengthwise and side gages movable toward each other further to position the last between them, fluid-operated means for 20 moving the side gages into their operative positions, and mechanism for admitting operating fluid to said fluid-operated means in response to pressure of the last on said toe-end gage.

25 35. In a machine for operating on shoe material mounted on lasts, the combination with means for operating on the material, of gage mechanism for positioning each last and its shoe material relatively to said operating means, said gage mechanism comprising a toe-end gage for 30 positioning the last lengthwise and side gages movable toward each other further to position the last between them, fluid-operated means for moving the side gages into their operative positions, valve mechanism for admitting operating fluid to 35 said fluid-operated means, and electromagnetic means controlled by said toe-end gage for operating said valve mechanism to admit the fluid in response to pressure of the last on said end gage.

36. In a machine for operating on shoe material mounted on lasts, the combination with means for operating on the material, of gage mechanism for positioning each last and its shoe material relatively to said operating means, said gage mechanism comprising a toe-end gage for 50 positioning the last lengthwise and side gages movable toward each other further to position the last between them, electrically controlled means for moving the side gages into their operative positions in response to pressure of the last on said toe-end gage and for maintaining them in those positions until electrical control of said means is terminated, and means for terminating said electrical control.

55 37. In a machine for operating on shoe material mounted on lasts, the combination with means for operating on the material, of gage mechanism for positioning each last and its shoe material relatively to said operating means, said gage mechanism comprising a toe-end gage for 60 positioning the last lengthwise and side gages movable toward each other further to position the last between them, electrically controlled means for moving the side gages into their operative positions in response to pressure of the last on said toe-end gage and for maintaining them in those

positions until electrical control of said means is terminated, and automatic means for terminating said electrical control independently of the toe-end gage while the last is still pressing on said end gage.

38. In a machine for operating on work, the combination with an operating tool, of a plurality of gages movable to position the work relatively to said tool by pressure on the work, another gage for further positioning the work relatively to said tool, and power-operated means controlled by said other gage for moving said first-named gages into their operative positions in response to pressure of the work against said other gage.

39. In a machine for operating on work, the combination with an operating tool, of a plurality of gages movable to position the work relatively to said tool by pressure on the work, another gage for further positioning the work relatively to said tool, power-operated means for moving said first-named gages into their operative positions, and electrical means controlled by said other gage for starting the operation of said power-operated means in response to pressure of the work against said other gage.

40. In a machine for operating on work, the combination with an operating tool, of a plurality of gages movable to position the work relatively to said tool by pressure on the work, another gage for further positioning the work relatively to said tool, fluid-operated means for moving said first-named gages into their operative positions, valve mechanism for admitting operating fluid to said fluid-operated means, and means for operating said valve mechanism to admit the fluid in response to pressure of the work against said other gage.

41. In a machine for operating on work, the combination with an operating tool, of gage mechanism for positioning the work relatively to said tool, said gage mechanism comprising a pair of gages geared together for swinging movements to position and clamp the work between them, a pair of shafts on which said gages are respectively mounted, another pair of gages also mounted on said shafts and geared together for swinging movements similarly to said first-named gages further to position and clamp the work, one of said pairs of gages being movable only by the turning of one of said shafts and the other pair being movable only by the turning of the other shaft, and yieldable means for turning both shafts.

42. In a machine for operating on work, the combination with an operating tool, of gage mechanism for positioning the work relatively to said tool, said gage mechanism comprising a pair of gages geared together for swinging movements

to position and clamp the work between them, a pair of shafts on which said gages are respectively mounted, another pair of gages also mounted on said shafts and geared together for swinging movements similarly to said first-named gages further to position and clamp the work, one of said pairs of gages being movable only by the turning of one of said shafts and the other pair being movable only by the turning of the other shaft, arms loosely mounted respectively on the different shafts, springs for turning the shafts by the swinging of said arms, and means for swinging said arms.

43. In a machine for operating on work, the combination with an operating tool, of gage mechanism for positioning the work relatively to said tool, said gage mechanism comprising a pair of gages geared together for swinging movements to position and clamp the work between them, a pair of shafts on which said gages are respectively mounted, another pair of gages also mounted on said shafts and geared together for swinging movements similarly to said first-named gages further to position and clamp the work, one of said pairs of gages being movable only by the turning of one of said shafts and the other pair being movable only by the turning of the other shaft, arms fastened respectively to said different shafts for turning them, other arms loosely mounted respectively on the different shafts, springs for operating said first-named arms by the other arms, and means for swinging said other arms.

44. In a machine for operating on work, the combination with mechanism arranged to operate on the work, of a gage for positioning the work relatively to said mechanism when the work is presented to the machine, fluid-operated means for effecting relative movement of the work and said mechanism to cause the latter to operate on the work, and mechanism controlled by said gage for admitting operating fluid to said fluid-operated means in response to pressure of the work on the gage.

45. In a machine for operating on work, the combination with mechanism arranged to operate on the work, of a gage for positioning the work relatively to said mechanism when the work is presented to the machine, fluid-operated means for effecting relative movement of the work and said mechanism to cause the latter to operate on the work, a valve for admitting operating fluid to said fluid-operated means, power-operated means for operating said valve thus to admit the fluid, and electrical means controlled by said gage for rendering said power-operated means effective thus to operate the valve.

BERNHARDT JORGENSEN.
